WALTER I. BROWN, OF OAKLAND, CALIFORNIA

METHOD OF MANUFACTURING GARMENT HANGERS

Application filed January 4, 1932. Serial No. 584,598.

My invention relates to a method of manufacturing bow-shaped wooden garment hangers which method is suitable for quantity production of hangers of this type. Hangers of this general type are usually provided with a wire hook or the like for suspending the hanger, but the present invention is particularly directed to the manufacture of the wooden body portion of such hangers.

It is a general object of the invention to devise a method which saves time, labor and expense in the manufacture of garment hangers of the character described.

Another object is to devise a method by which a plurality of garment hangers can be manufactured simultaneously from a single piece of stock.

These and other objects and advantages are attained in the two species of my method having the steps illustrated in more or less diagrammatic form in the accompanying drawings, in which:

Fig. 1 is a perspective view illustrating apparatus suitable for performing the first step in each of the methods.

Fig. 2 is an elevational view of apparatus for performing the second step in one of the preferred methods.

Fig. 3 is an elevational view of apparatus which can be used for performing the third step.

Fig. 4 is an elevational view of apparatus which can be used for performing the fourth and final step of the first method.

Fig. 5 is a cross sectional view taken along the plane indicated by line 5—5 of Fig. 2.

Fig. 6 is a cross sectional view taken along the plane indicated by line 6—6 of Fig. 3.

Fig. 7 is a cross sectional view taken along the plane indicated by line 7—7 of Fig. 4.

Fig. 8 is an elevational view illustrating apparatus which can be utilized in performing the second step of a modified method.

Fig. 9 is an elevational view of apparatus which can be utilized in performing the third and final step of the modified method.

Fig. 10 is a cross sectional view taken along the plane indicated by line 10—10 of Fig. 8.

Fig. 11 is a cross sectional view taken along the plane indicated by the line 11—11 of Fig. 9.

Fig. 12 illustrates apparatus for performing an additional step which can be included in each of the methods, if desired.

Briefly, the method of forming garment hangers to which this invention is directed comprises cutting from a piece of stock a bow-shaped block of wood having a length and height substantially equal to the corresponding dimensions desired in the finished hanger and having a width which is several times as great as the width of the finished hanger. From this block a plurality of hangers are to be manufactured, preferably simultaneously, and the second step in the method comprises cutting spaced grooves in the top or in the bottom of the block to subdivide the block into a plurality of portions, each having a width which is substantially equal to the width desired in the finished hanger, and leaving a relatively narrow web for retaining the several portions together to facilitate subsequent operations. Thereafter, the top side of each of the hangers can be rounded or given any other desired shape and then the hangers can be severed from one another either by cutting through the web at the crucial points or by removing the web entirely. Either before or after the hangers have been separated, a hole can be bored vertically through the center of each hanger for receiving a suspending hook or the like.

Referring now to the drawings and first to Figs. 1 to 7 thereof, I have illustrated the steps of one of my preferred methods. In Fig. 1 a suitable saw 16 is shown for cutting bow-shaped blocks 17 from a piece of stock 18. The saw 16 can be a band saw if desired, but I prefer to employ a saw of cylindrical shape as shown, the radius of curvature of the saw being substantially equal to the radius of curvature desired in the curved side of the finished hanger. Each of the blocks 17, therefore, has a longitudinal contour which corresponds generally to the contour desired in the finished hanger. The piece of stock 18 is preferably previously cut to a size such that the length l of the block 17 equals the length desired in the finished hangers and the width w of the block 17 is as great as some multiple of the width desired in the finished hanger, due allowance being made for saw cuts which are to be made subsequently to sever the hangers from one another. The dimension w will be determined in each instance by the number of hangers it is desired to produce simultaneously. The height h of each of the blocks 17 is preferably made substantially equal to the corre-

sponding dimension of the finished hanger, allowance being made if material is to be removed along this dimension in subsequent operations.

5 After the block 17 has been cut from the piece of stock 18 a plurality of grooves 19 can be formed therein to sub-divide the block into a plurality of portions 21 each having a width corresponding to that desired in the finished hangers. For performing this operation a buzz saw can be employed having a plurality of blades 22 each being spaced from an adjoining blade by an amount which is equal to the width desired in the finished hangers. Preferably, the depth of the grooves 19 is such that it is somewhat less than the dimension h of the block 17 so that an integral web 23 is left which interconnects the portions 21. Web 23 serves to retain the portions 21 together so that subsequent operations can be performed on all of the portions 21 simultaneously.

23 While the portions 21 are thus secured together, the upper edge 24 of each of the portions can be rounded or bevelled or given any other desired contour by any suitable means. In Figs. 3 and 6 I have shown a pair of rotatable cutters 26 and 26' having cutting edges 27 and 27' for rounding the upper edges on all of the portions 21 simultaneously. One of the cutters, such as the cutter 26, can be rotated in a counterclockwise direction and serves to shape approximately one-half of the upper edge of the portions 21 when the stock 30 is moved in the direction of the arrow shown in Fig. 3, while the other cutter 26' rotates in the opposite direction and begins where the cutter 26 leaves off to shape the remaining part of the upper edges 24. Preferably, suitable means, such as that disclosed in my co-pending application, Serial No. 584,597, filed January 4, 1932, can be provided for moving the cutters 26 and 26' to and from the work at the beginning and end of their respective cutting operations. If desired, the part cut by cutter 26 can overlap slightly the part cut by the cutter 26', thereby rendering the surface cut continuous in appearance. The point at which the changeover from one cutter to the other occurs is preferably the point at which the first cutter would begin to cut against the grain of the wood if it were allowed to continue the cutting operation. If this point in the stock occurs elsewhere than 35 at the approximate center, the changeover position between the cutters can be displaced accordingly, so that both cutters will cut with the grain and produce a smooth surface. Preferably, however, the stock is arranged so that its grain runs lengthwise of the hangers since the finished product possesses greater strength under this condition. After 40 this edge shaping operation, each of the portions 21 has the contour and the dimensions desired in the finished hanger.

To separate the portions 21 from each other a rotatable saw 28 can be employed having a plurality of spaced blades 29 which are adapted to sever the web 23 between all of the adjoining portions 21. By providing 45 a tapered cutting edge 31 on each of the blades 29 the lower edge of each of the hangers can be bevelled, as at 32, during this operation. After the severing operation, the hanger is substantially completed, the only remaining 50 operation being to bore a vertical hole through the center of each hanger for receiving a hook or the like for suspending the hanger. A drill or bit 33 is shown in Fig. 55 12 for performing this operation. If desired, however, a hole may be bored in each of the portions 21 before they are severed from one another, in which event all of the holes can be bored simultaneously by a gang 60 drill designed for this purpose.

In Figs. 8 to 11 I have illustrated the steps of a method which is slightly modified in that a retaining web 34 is left near the top edge of the hangers instead of at the lower edge. In this instance, a gang saw having a 65 plurality of spaced blades 36 cuts grooves in the lower side of the block 17 instead of in the upper side. Thereafter a pair of rotatable cutters 37 and 37', similar to the cutters 26 and 26' shown in Figs. 3 and 6, can be employed for shaping the upper edges on all of the hangers simultaneously and in the same 70 operation cut through the web 34 holding the hangers together. Thus, in the method illustrated in Figs. 8 to 11, the shaping step and the severing step are combined and are performed together.

75 By providing a retaining web, such as the web 23 or the web 34, for securing all of the hanger body portions together while the various shaping operations are performed, manufacture of the hangers in groups is greatly facilitated, since the individual operations can be performed on all of the hangers simultaneously just as easily as the same 80 operation could be performed on a single hanger, thus resulting in a substantial saving in time, labor and expense in the quantity production of articles of this character.

105 I claim:

The method of manufacturing bow-shaped garment hangers and the like from material having a grain which comprises cutting from a piece of stock a bow-shaped block having at least one curved edge crossing the grain in different directions in different parts of the block, cutting a plurality of spaced grooves almost through said block to subdivide the block into a plurality of portions secured together by a relatively thin web, finishing said curved edge of each of said portions by a plurality of cuts each in the direction of said grain, and separating each of said portions at said web.
